UNITED STATES PATENT OFFICE.

SAMUEL G. SHAPIRO, OF NEW YORK, N. Y.

SHOE-HEEL.

1,356,227.

Specification of Letters Patent. Patented Oct. 19, 1920.

Application filed June 14, 1919. Serial No. 304,129.

To all whom it may concern:

Be it known that I, SAMUEL G. SHAPIRO, a citizen of the United States, residing at New York, in the county of New York and State of New York, have invented certain new and useful Improvements in Shoe-Heels, of which the following is a full, clear, and exact description, such as will enable others skilled in the art to which it appertains to make and use the same.

This invention relates to shoe heels, and with respect to its more specific features, to improved metallic heels and their construction for attachment to shoes.

It is the primary object of the invention to provide improved heels of metal or the like which may be inexpensively manufactured and which are capable of expeditious and firm attachment to shoes, either when the latter are manufactured or when repaired.

It is a further object to provide a structurally superior and functionally advantageous durable heel which is adapted for long service and which may be readily removed from outworn shoes and readily reattached to others.

Other objects and advantages will be in part noted hereinafter in connection with the following description of the accompanying drawing which illustrates preferred embodiments of the invention, and in which,

Figure 1 is a side elevation of the improved heel attached;

Fig. 2 is a similar view, partially in section, of the heel detached;

Fig. 3 is an elevation of one attaching means;

Fig. 4 is a side view, partially in section, of the heel provided with another form of attaching means;

Fig. 5 is an elevation of the attaching means of Fig. 4, and

Fig. 6 is a bottom plan of a shoe adapted for attachment thereto of the heel shown in Fig. 4.

The heel shown includes in general a hollow body portion 1 of cast metal or other durable material and a lower thread part or lift 2 of shock-absorbent material such as leather or rubber. Heels of this character are particularly adapted for women's shoes, and may be conveniently shaped in the high French style, or medium Cuban style as shown. It is to be under-

stood, however, that the invention is not limited in this respect.

Referring more particularly to the drawing, there is shown in Fig. 2 a heel body 1 having relatively thin walls 3 which, however, are of increased thickness at spaced upper points 4. These points 4 are preferably located at the front corners, the middle sides, and the center rear of the upper edges, and at the time the metal heels are cast screw threaded sockets 5 are cast therein. As shown in Figs. 2 and 3, sockets 5 are relatively short and shaped with an exterior groove 6 and knurled walls 7, whereby when seated in the heel walls 4, the sockets are securely anchored against axial withdrawal and relative rotation. To coöperate with the sockets, there are provided sharpened pins or studs 8 having straight threaded shanks which screw into the inner bore of the sockets. In attaching the heels, pins 8 are first inserted in the holders 5, and then the heel affixed by driving from below to project the pins through the shoes. The pins are then clenched and may be covered over.

It will be noted that a primary advantage of the construction above described resides in the capability of removing and replacing the pins 8. That is to say, the heel may thus be readily and securely affixed to a shoe, and later removed therefrom while still permitting its subsequent firm attachment merely by replacing the old bent pins by new pins. Thus the service of the heel is in no way limited to the service of a particular shoe. Likewise, of course, in case any of the pins 8 are bent in originally installing the heel, such pins may be replaced so that it is not necessary to discard the heel or depend for its attachment on less than the full number of fastening elements.

In Fig. 4 the heel walls are provided with sockets 5 of increased length above the exterior groove 6. In this form, the sockets are set to project slightly above the adjacent surface of the heel walls, and also, the pins 8 (Figs. 2 and 3) are replaced by flat headed screws 9. This construction is especially adapted for use where the heels are attached to the shoes in the original manufacture thereof, and in such use, the shoe bottoms may be provided with spaced recesses 10 (Fig. 6) adapted to receive the projecting ends of the elongated sockets 5 whereby correct positioning of the heel is facilitated

and its stability, when attached, increased. In this form, also, the screws 9 are adapted to pierce the shoe bottom from the inside and take into the boxes of the corresponding 5 sockets 5.

It will thus be noted, that heels as described, may be adapted for attachment either by pins from the outside or by screws, preferably having flat and relatively large 10 heads so as to give a smooth surface, from the inside. In both forms, moreover, the heel is capable of easy and quick removal, when desired for repairs or otherwise, and may at all times be readily re-attached with 15 unimpaired security.

Having described my invention, what I claim is new, and desire to secure by Letters Patent is:

1. In combination, a shoe having a bottom 20 portion to receive a heel and provided with a plurality of spaced recesses, a heel having a plurality of projecting portions to fit said recesses, and fastening means to penetrate the shoe bottoms and take into said heel projecting portions.

2. In combination, a shoe having a bottom

portion to receive a heel, said portion being provided with a plurality of spaced recesses, a metallic heel having a plurality of interiorly threaded sockets anchored therein, 30 said sockets projecting slightly above the adjacent heel surface and spaced to fit said shoe recesses, and removable headed screws to penetrate said shoe bottom and thread into said sockets.

3. In combination an aluminum heel, and sockets cast into the portion of the aluminum heel adjacent to shoe, for anchorage against relative rotation and axial displacement, said sockets having threaded bores and removable threaded fastening elements adapted to screw into said sockets, and the points of which are driven into the shoe and clenched therein to fasten the heel to the 40 shoe.

In testimony whereof I affix my signature, in the presence of two witnesses.

SAMUEL G. SHAPIRO.
